* cited by examiner

Primary Examiner—Catherine Tuttle(74) Attorney, Agent, or Firm—J. Bennett Mullinax, LLC(57) CLAIM

The ornamental design for a pattern of dimples on a golf ball, as shown and described.

DESCRIPTION

The sole FIGURE is a plan view of a pattern of dimples on a golf ball design showing our new design, the portions shown in broken lines being for illustrative purposes only, and forming no part of the claimed design.
